LOCOMOTIVE DRAFT APPLIANCE

Filed Oct. 4, 1929

UNITED STATES PATENT OFFICE

HUGH ROONEY AND HUGH K. ROONEY, OF MUSKOGEE, OKLAHOMA

LOCOMOTIVE DRAFT APPLIANCE

Application filed October 4, 1929. Serial No. 397,316.

The object of this invention is to provide a simple mechanism whereby the exhaust steam from a locomotive will be utilized to expedite the discharge of smoke and to create a steady even draft through the fire-box and the boiler so that the fire will burn steadily and consume fuel economically while maintaining the desired boiler pressure. The invention is illustrated in the accompanying drawings and 10 will be hereinafter fully set forth.

In the drawings:

Figure 1 is a vertical longitudinal section through a portion of the smoke box of a locomotive having the invention embodied there- 15 in,

Fig. 2 is a view, partly in transverse vertical section and partly in front elevation of the same mechanism.

The smoke box 1 of the locomotive may be 20 of any well known or approved construction, and in Figs. 1 and 2, there is shown within the smoke box the usual deflector 2 extending downwardly and forwardly from the flue sheet 3 in which the front ends of the flues 4 are secured. In the upper portion of the smoke box is a hood 5 leading directly to the smoke outlet pipe 6 and aligned with the smoke outlet 6 is a pipe 7 through which exhaust steam passes from the exhaust nozzle 8 to 25 create a draft through the smoke box whereby the smoke, cinders and sparks drawn through the boiler flues will be sucked toward the outlet pipe 6, the smoke being discharged through said outlet and the cinders and 30 sparks being arrested by a screen 9, which extends between the deflector 2 and the front end of the smoke box, and collected in the bottom of the smoke box in the usual manner.

In carrying out the present invention, the 40 pipe 7 is secured in a base 10 which, in turn, is secured upon the exhaust nozzle 8 and in the said pipe 7 adjacent the ends thereof are mounted anti-friction thrust bearings 11 in which are journaled the end portions of a 45 vertically disposed shaft 12 having spiral blades 13 secured upon its lower portion, said blades or vanes being of such diameter as to extend close to the inner circumference of the pipe 7, as clearly shown in Fig. 1. Fixed to 50 the upper end of the shaft 12 is a spider 14

and about said spider is secured a sleeve or tube 15 upon the exterior of which is fixed a fan 16, as shown. The fan 16 may be of any approved form and we have shown it as composed of an inner ring or hub secured upon the outer circumference of the sleeve 15 by brazing or other approved means and blades 18 extending radially from said hub or inner ring to a circumferential ring 19, the outer ends of the blades or vanes being secured to the circumferential ring 19 so that a rigid firm structure will result.

Fixed upon the sleeve 15 below the fan is a beveled gear 20 with which meshes a pinion 21 secured on the inner end of a shaft 22 which is journaled in a bracket 23 carried by the pipe or tube 7 and in the side wall of the smoke box, extending through said wall, as shown in Fig. 2. Upon the outer side of the smoke box is mounted a shelf 24 upon which is supported a turbine casing 25, the outer extremity of the shaft 22 extending through said casing and being journaled in the sides of the same. Within said casing is a turbine fixed to the shaft 22 and arranged to be driven by live steam from the locomotive boiler, a pipe 27 leading the steam to the inlet steam chest of the turbine so as to cause the steam to play upon the vanes of the turbine disk and thereby rotate the same. The steam escapes through the central portion of the turbine disk around the shaft 22. The inflow of steam to the turbine casing is controlled by a valve which is connected to the upper end of a lever 31 fulcrumed between its ends upon the side of the turbine casing and having its lower end connected to a centrifugal speed governor 32.

The rotation of the shaft 22 by the turbine will act through the described gearing to rotate the sleeve 15 and the fan 16 carried by said sleeve to accelerate the draft through the smoke box sufficiently to prevent the smoke accumulating and to maintain a steady draft through the fire-box so that the fuel 55 will be consumed evenly and not jerked through the boiler flues. If the locomotive is running and has acquired some speed, the passing of steam to the turbine is cut off by the action of the centrifugal governor. The

exhaust steam flowing from the nozzle 8 through the pipe or conduit 7 will then act upon the spiral blade 13 so as to rotate the shaft 12 to which it is secured. Inasmuch as 5 the sleeve 15 is fixed to the upper end of the shaft 12, it will be rotated and the fan will, consequently, be operated to maintain the desired steady draft through the fire. After 10 the speed attained causes the governor to close the turbine valve, the fan will be driven solely by the exhaust steam.

In order that the speed of the fan may be reduced when the locomotive is working hard and driving the fan too fast, by-pass pipes 15 39 are provided in the smoke box and valves 40 are disposed in the exhaust chamber to control said pipes.

Having thus described the invention, we claim:

20 A locomotive draft appliance comprising in combination with a smoke box having a nozzle for admitting exhaust steam in its bottom, a smoke outlet in its top alined with said nozzle and a straight cylindrical pipe 25 connected at its lower end to said nozzle and having its upper end disposed under and alined with the smoke outlet, a shaft disposed axially within said pipe, a spiral blade on said shaft extending longitudinally thereof 30 and fitting close to the wall of the pipe, bearings for said shaft within said pipe and near the ends thereof, the blade extending between and terminating near said bearings whereby to present an extended surface to the action 35 of the steam entering through the nozzle, a spider fixed to the upper end of the shaft, a sleeve fixed about the spider and fitting in and projecting upwardly from the upper end of the pipe toward the smoke outlet and terminating near said outlet, and a fan having a 40 hub encircling and secured to said sleeve above the upper end of the cylindrical pipe.

In testimony whereof we affix our signatures.
